FIG. 4

UNITED STATES PATENT OFFICE

2,335,900

BLACK-OUT CONTROL SYSTEM

Fred B. Aubert, Grosse Pointe, Mich.

Application April 21, 1942, Serial No. 439,899

9 Claims. (Cl. 171—97)

This invention relates to an electrical circuit controlling system and more particularly to a system which has already been installed and wherein it is desired to control one or more circuits.

The system is especially useful in blacking-out, during an air raid, desired light and other circuits in buildings which have been constructed and equipped with the usual wiring for light and power circuits. The system is also highly desirable for blacking-out electrically illuminated sign boards and advertising displays which may be included in a circuit system which it is desired to maintain energized.

One object of the invention is to provide means by which one or more selected normally closed circuits can be automatically interrupted and reinstated.

Another object is to provide a control system by which the main circuit controlling switch can be utilized as the control initiating device.

Another object is to provide a system in which branch circuits can be controlled from a remote central station.

The invention consists in the novel circuit arrangement and in the control means operative therein and supervising energization.

In the accompanying drawing, to be taken as a part of this specification, there are fully and clearly illustrated several preferred embodiments of the invention, in which drawing:

Figure 1 is a diagrammatic view showing the installation of the control system;

Fig. 2 is a diagrammatic detail view showing a control device of the system in black-out position;

Fig. 3 is a diagrammatic detail view similar to Fig. 2 but showing the control means in a main circuit open position, and

Fig. 4 is a detail diagrammatic view of another form of control means for use in the system.

Referring to the drawing by characters of reference, 1 designates generally a building such as a residence, office building or factory having a basement room 2 below or partly below the ground level 3, a first floor having rooms 4, 5 and a second floor having rooms 6, 7. Leading into the room 2 from the exterior of the building there is a main electric power line having lead wires 8, 9 controlled by a main switch 10 at the control station. The switch 10 controls current flow to a fuse panel 11 having terminals 12, 13, 14 and 15 connected by a lead wire 16 to the switch 10 for connection to lead wire 9. The panel also has terminals 17, 18, 19 and 20 paired

respectively with the terminals 12, 13, 14 and 15 and which are connected to a return lead wire 21 connecting to the switch 10 and therethrough to the lead wire 8. Connected across the terminals 12 and 17 by lead wires 22, 23 respectively there is an electric power operated or motor driven means 24, such as an electric refrigerator, positioned within the first floor room 4. The terminals 13 and 18 have lead wires 25, 26 respectively connected thereto from which branch lead wires 27, 28 are connected to a light bulb 29 in the room 4, a control switch 30 being positioned in the lead wire 27 and controlling operation of the light bulb 29. From the wires 25, 26 there also extend lead wires 31, 32 respectively to a light bulb 33 in the room 5 and controlled by a switch 34 in the lead wire 31. The circuit 25, 26 is controlled by a control device 34a positioned in the room 2 and having a relay switch 35. The terminal 18 is connected to the return line wire 21 through the relay switch 35 having contacts 36, 37 connected by lead wires 38, 39 respectively to the terminal 18 and to the wire 21. The contact 36 is carried by the pivoted relay operating arm or armature 40 and urged toward open position by a spring 41. An electromagnet 42 cooperates with the armature 40 to pull the contacts 36, 37 into circuit closed position and is energized through lead wires 43, 44 connected to the switch 10 by lead wires 16 and 21 respectively. Cooperable with the arm 40 there is an electrically energized stop means 45 which includes an electro-magnet 46 and an armature 47 urged by a spring 48 out of blocking or stopping position and into engagement with an adjustable stop screw 49. The armature 47 carries a resilient member 50, such as a leaf spring, which, when the contacts 36, 37 are closed, is in tensioned abutting engagement with the end of the arm 40. The spring 50 is however of such length that when the magnet is deenergized, the arm 40 will move sufficiently so that inherent resilience of spring 50 will move it into vertical or endwise opposing relation to the arm 40 so that the contacts 36, 37 are blocked from movement to closed position as in Fig. 2. The magnet 46 is energized by direct current from any suitable source, such as a full wave rectifier 51, which is connected by lead wires 52, 53 to the lead wires 16, 21 respectively. Connected across the lead wires 54, 55 from the rectifier to the magnet 46 and in parallel therewith there is a fixed condenser 56 which serves to delay energization of the magnet 46 upon closure of the switch 10 and which serves to maintain the mag-

net 46 energized, i. e. its deenergization is delayed, for a time period following opening of the switch 10. The terminals 14 and 19 are connected by lead wires 57, 58 respectively to a fuse panel 59 positioned on the second floor, for example, and in the room 7. The fuse panel terminals 60, 61 to which the lead wires 57, 58 respectively are connected, are connected in the room 6 by the lead wires 62, 63 to a light bulb 64 which is controlled by a switch 65 in the lead wire 62. Other terminals 66, 67 of panel 59 are connected by lead wires 68, 69 respectively to a light bulb 70 in the room 7, this bulb being controlled by a switch 71 in the lead wire 68. The circuit 68, 69 of bulb 70 is controlled by a control device 72 similar in all respects to the control device 34^a, and therefore repetition of description being unnecessary the primes of reference characters applied to device 34^a designate like parts in the device 72. The terminal 67 is connected by lead wire 38' to the relay switch terminal 36'. From the relay fixed contact 37' the lead wire 39' connects to the lead wire 58 through a lead wire 73. The lead wire 57 is connected by a lead wire 74 to the rectifier lead wire 52' and the magnet lead wire 43'. The lead wire 57 is connected to the lead wire 68 by a lead wire 75 connected between the terminals 60 and 66. The light bulb 76 in the basement room 2 is connected by lead wires 77 and 78 to the panel terminals 20 and 15 respectively. The fuse panels 11 and 59 are provided with the usual power limiting safety fuses, as is diagrammatically illustrated.

The operation of the black-out control system is as follows: Assuming that the main switch 10 is closed, as shown, so that power is supplied from the main line 8, 9 to the panel 11, the control devices 34^a and 72 will each be in the positions shown, and since each of switches 36, 34, 65 and 71 is closed, current will be supplied to each of the power consuming devices in the building 1. If now information is received by the operator stationed at, or promptly arriving at, the switch 10 that the light sources or bulbs in those rooms which are not protected against light leakage to the exterior of the building are to be extinguished or blacked-out, then the operator will manipulate the system as follows: The switch 10 will be opened and substantially instantaneously closed or with a delay which is not longer than the time period during which the condensers 56 and 56' can maintain energized the electro-magnets 46 and 46' respectively. Accordingly, the opening of switch 10 will instantaneously deenergize the relay switch magnets 42 and 42' so that the armatures 40 and 40' will be moved upward to circuit opened position, as shown in Fig. 3, under the force of their springs 41 and 41' respectively. Since the magnets 46 and 46' are maintained energized by the condensers 56 and 56' respectively the leaf springs 50, 50' respectively will snap into blocking position, as in Fig. 2, and be in the path of closing movement of the arms 40, 40' respectively. As the switch 10 is immediately closed upon opening of the switches 36 and 35', the current flow to the rectifiers 51, 51' will be reinstated so that the armatures 47, 47' will be held without movement in the position of Figs. 1 and 2. The closure of switch 10, of course, reenergizes the relay switch magnets 42, 42', but since the leaf springs 50, 50' are in blocking position the armatures 40, 40' can only be pulled by their respective magnets into abutting engagement with the ends of the armature leaf springs 50, 50' and, accordingly, the circuits 38,

39 and 38', 39' are maintained open. This will result in the lights 64 and 76 and the power means 24 being maintained energized and the lights 29, 33 and 70 being blacked-out or extinguished.

When the operator is advised that illumination of the bulbs 29, 33 and 70 is again permissible as by the all clear signal, the switch 10 will be opened and held open for a sufficient time of say five to ten seconds, which will be sufficient to discharge the condensers 56, 56'. The armatures 47, 47' will, therefore, be released by their respective magnets 46, 46' and move to the position shown in Fig. 3, the armatures 40, 40' having prior thereto, of course, moved to the position shown in Fig. 3. If now the switch 10 is closed, the condensers 56, 56' will delay the reenergization of magnets 46, 46' upon the reenergization of the magnets 42, 42' so that the armatures 40, 40' will move to closed position and into the path of movement of the leaf springs 50, 50' respectively so that when the magnets 46, 46' are energized, the leaf springs 50, 50' will again be tensioned, as in Fig. 1, against the armatures 40, 40' and be in the ready position for blocking the armatures in open circuit position upon reopening of the switch 10.

The form of invention shown in Fig. 4 utilizes, in lieu of the magnet 46 and armature 47 and the rectifier 51, an electrically energized heat motor 80, such as a bimetal warping blade, having a resistance heat coil 81 connected by lead wires 82, 83 to the lead wires 16, 21 respectively. The bimetal blade 80 is cooperable with the armature 40 of the relay switch 35 in the same manner as the leaf spring 50. It will be apparent that upon opening of the main switch 10 that the tensioned blade 80 will snap into vertical position and endwise blocking relation to the return closing movement of the relay armature 40. Since the blade 80 will take an appreciable time to cool after opening of the switch 10, the switch 10 may be closed to reenergize the coil 81 and the current consuming means 24, 64 and 76 before the blade 80 moves out of opposing relation to closure of the switch contacts 36, 37. It will also be apparent that the blacked-out circuits can be reinstated by opening switch 10 and then delaying its closure for a sufficient time to permit the bimetal blade 80 to cool so that it moves to the dotted line position designated 84 which is out of blocking relation to the armature 40. Thereupon, closure of switch 10 will result in the parts again taking the position of Fig. 4 with all of the building circuits again supplied from the main line lead wires 8, 9.

Having thus described my invention, what is claimed and is desired to be secured by Letters Patent of the United States is:

1. In an electrically operated black-out control system having a controlled circuit to be interrupted and reinstated automatically at will and having another circuit to be maintained operative during black-out of the controlled circuit, a main switch controlling the current supply to the circuits, a relay switch having contacts connected in and controlling the controlled circuit, said relay switch being electrically connected to and controlled by said main switch, and electrically operated means controlled by said main switch and controlling closure of said relay switch.

2. In an electrically operated black-out control system having a controlled circuit to be interrupted and reinstated automatically at will

and having another circuit to be maintained operative during black-out of the controlled circuit, a main switch controlling the current supply to the circuits, a relay switch having contacts connected in and controlling the controlled circuit, said relay switch being electrically connected to and controlled by said main switch, and electrically operated delayed action means controlled by said main switch and controlling closure of said relay switch, said delayed action means moving upon opening of said main switch, first into and then out of opposing relation to closure of said relay switch.

3. In an electrically operated black-out control system having a controlled circuit to be interrupted and reinstated automatically at will and having another circuit to be maintained operative during black-out of the controlled circuit, a main switch controlling the current supply to the circuits, a relay switch having contacts connected in and controlling the controlled circuit, said relay switch being electrically connected to and controlled by said main switch, stop means movable into and out of opposing relation to closure of said contacts, and electrically operated means controlled by said main switch and controlling operation of said stop means.

4. In an electrically operated black-out control system having a controlled circuit to be interrupted and reinstated automatically at will and having another circuit to be maintained operative during black-out of the controlled circuit, a main switch controlling the current supply to the circuits, a relay switch having contacts connected in and controlling the controlled circuit, said relay switch being electrically connected to and controlled by said main switch, stop means movable into and out of opposing relation to closure of said contacts, electro-magnetic means controlling operation of said stop means, means to supply direct current to said electro-magnetic means and controlled by said main switch, and a condenser in parallel circuit with said electro-magnetic means to delay operation of said stop means upon opening and closing of said main switch.

5. In an electrically operated black-out control system having a controlled circuit to be interrupted and reinstated automatically at will and having another circuit to be maintained operative during black-out of the controlled circuit, a main switch controlling the current supply to the circuits, a relay switch having contacts connected in and controlling the controlled circuit and having an operating arm, delayed-action stop means controlled by said main switch and having a resilient portion movable into a blocking position in the path of contact closing movement of said relay switch, said arm having a portion positioned in the path of movement into blocking position of said resilient portion when said contacts are closed, said delayed-action means moving said resilient portion toward blocking position subsequent to closure of said contacts so that said resilient portion is tensioned against said arm, said delayed-action means holding said resilient portion in position for movement under its resilience into blocking position upon opening of the main switch.

6. In an electrically operated black-out control system having a controlled circuit to be interrupted and reinstated automatically at will and having another circuit to be maintained operative during black-out of the controlled cir-

cuit, a main switch controlling the current supply to the circuits, a relay switch having contacts connected in and controlling the controlled circuit and having an operating arm, an electro-magnet controlled by said main switch, an armature operable by said electro-magnet and having a resilient portion movable into a blocking position in the path of contact closing movement of said arm, said arm having a portion positioned in the path of movement into blocking position of said resilient portion when said contacts are closed, and means to delay movement of said armature upon operation of said main switch so that said arm will be positioned to block said resilient portion upon closure of said main switch and said resilient portion will move into blocking position upon opening of said main switch.

7. In an electrically operated black-out control system having a controlled circuit to be interrupted and reinstated automatically at will and having another circuit to be maintained operative during black-out of the controlled circuit, a main switch controlling the current supply to the circuits, a relay switch having contacts connected in and controlling the controlled circuit and having an operating arm, an electro-magnet controlled by said main switch, an armature operable by said electro-magnet and having a resilient portion movable into a blocking position in the path of contact closing movement of said arm, said arm having a portion positioned in the path of movement into blocking position of said resilient portion when said contacts are closed, and a condenser in parallel circuit with said electro-magnet to delay movement of said armature upon operation of said main switch so that said arm will be positioned to block said resilient portion upon closure of said main switch and said resilient portion will move into blocking position upon opening of said main switch.

8. In an electrically operated black-out control system having a controlled circuit to be interrupted and reinstated automatically at will and having another circuit to be maintained operative during black-out of the controlled circuit, a main switch controlling the current supply to the circuits, a relay switch having contacts connected in and controlling the controlled circuit and having an operating arm, resilient stop means movable into position to block closure of said contacts when said contacts are in open position, said operating arm blocking movement of said stop means into blocking position when said contacts are in closed position, electrically operable means controlled by said main switch and operable to move said stop means toward and from its blocking position and to hold said stop means tensioned against said arm, and means to delay energization and deenergization of said electrically controlled means upon closing and opening respectively of said main switch so that upon quick successive opening and closing of said main switch, said relay switch will open and be blocked open and so that upon opening and delayed closing of said main switch, said relay switch will be closed.

9. In an electrically operated black-out control system having a controlled circuit to be interrupted and reinstated automatically at will and having another circuit to be maintained operative during black-out of the controlled circuit, a main switch controlling the current supply to the circuits, a relay switch having contacts connected in and controlling the controlled circuit and having an operating arm, resilient stop means

movable into position to block closure of said contacts when said contacts are in open position, said operating arm blocking movement of said stop means into blocking position when said contacts are in closed position, an electro-magnet operable to move said stop means toward its blocking position and to hold said stop means tensioned against said arm, a rectifier to supply direct current to said electro-magnet and controlled by said main switch, and a condenser 10

in parallel circuit with said electro-magnet to delay energization and deenergization of said electro-magnet upon closing and opening respectively of said main switch so that upon quick successive opening and closing of said main switch, said relay switch will open and be blocked open and so that upon opening and delayed closing of said main switch, said relay switch will be closed.

FRED B. AUBERT.
